REUBEN ERICH, OF SAN JOSE, CALIFORNIA.

MECHANICAL MOVEMENT.

Application filed October 19, 1926. Serial No. 142,639.

- It is the object of the invention to provide a simple and efficient mechanism whereby rotary motion may be transformed into linear motion.
- 5 It is also an object of the invention to provide a movement of the character indicated particularly adapted to transform the rotary motion of a crank shaft of an engine to linear motion as applied to the engine 10 piston, and vice versa.
- In the drawing:
- Figure 1 is a diagrammatical illustration of the method of operation of a device embodying my invention.
- 15 Figure 2 is an illustration of the device as constructed for use in connection with the piston of an internal combustion engine.
- Considering the power to be applied to the device through the medium of piston 1, 20 then the shaft 2 may be termed the driven shaft.
- On the driven shaft 2 is keyed a gear 3 and meshing with the gear 3 are two smaller gears 4 and 5 respectively. These gears 4 25 and 5 bear any desired ratio to the gear 3 and are mounted diametrically opposite each other as shown, on crank shafts 6 and 7 the arms 8 and 9 being angularly arranged relative to each other as hereinafter 30 more fully set forth.
- On pins 10 and 11 of crank shafts 6 and 7 are mounted links 12 and 13, these links being journaled upon the piston 1 as shown at 14.
- 35 In order that the assembled parts may function in the manner hereinafter described it is necessary that they be properly proportioned and arranged. This proportioning and arranging is accomplished in 40 the following manner, using the diagram in Figure 1 for the purpose of illustration.
- Starting with the given line A—B it is 45 first divided into five equal parts. With A as a center describe a circle C, and with B as a center and the same radius describe a circle D. Lay off the angle BAE equal to 130° and the angle ABF equal to 130° thereby securing the radii G and H respectively. 50 Erect the perpendiculars AI and BJ to the radii AE and BF, which perpendiculars intersect at K. Connect KE with the line L and KF with the line M. It follows, of course, that AE and BF are equal and also that KE and KF are equal, and that 55 K lies in the perpendicular bisector of AB.
- If the two radii G and H are now rotated
- about their pivotal points A and B with equal angular velocity in the same direction the point K will move in a straight line parallel with the line AB, reciprocating between the points K' and K².
- An important feature in this construction is the angle described by the radius G (and of course H) in the two opposite movements of the point K; that is, from K' to K² and from K² to K'. Assuming the point K to be at K', then E will be at E' and F at F'. Now, while K' moves to K² the radius G will swing through the arc N, E' moving to E². The radius H will move 70 through a similar arc to F². It may be seen therefore, that in moving K' in a straight line to K² the radii G and H have described arcs of approximately 220°. Obviously, then, the return movement of K² to K' can 75 only carry the radii G and H from E² to E' and from F² to F', through an arc of approximately 140°.
- If, now, the mechanism shown in Figure 2 is constructed in accordance with the foregoing disclosure with the gear 3 inserted as shown, the circular pitch lines of the two gears 4 and 5 corresponding with the circles C and D, the arms 8 and 9 corresponding with the radii G and H, and the links 12 and 13 corresponding to the lines L and M, the piston 1 will be reciprocated along the straight line K' K², while a rotary motion will be imparted to the shaft 2.
- In accurately plotting the path of travel 90 of the point K it is found that while it travels in a straight line in one direction it forms a slight loop at each end of its path of travel in the opposite direction as indicated at 14. This loop is so slight, however, that it may be entirely disregarded in the practical application of the principle to a working mechanism.
- It is to be understood, of course, that while I have herein shown and described but 100 one specific embodiment of the invention, changes in form, construction and method of operation may be made within the scope of the appended claims.
- 105 I claim:
1. A mechanical movement comprising a pair of spaced revoluble cranks of equal length on spaced parallel axes and means for driving the same at equal angular velocities in the same direction, and links of equal length pivotally connected to each other on a common axis movable in a plane 110

substantially parallel with said first mentioned axes and to said cranks at equal distances from their axes of rotation.

2. A mechanical movement comprising a pair of spaced revoluble cranks of equal length positioned at given equal angles to a straight line passing through their axes of rotation and means for driving the same at equal angular velocities in the same direction, and links of equal length pivotally connected to each other on a common axis movable in a plane substantially parallel with the plane of axes of said cranks and to said cranks at equal distances from their axes of rotation.

3. A mechanical movement comprising a pair of spaced revoluble cranks of equal length positioned at angles of fifty degrees to a straight line passing through their axes of rotation and oppositely directed relative to a perpendicular bisector of said line and means for driving the same at equal angular velocities in the same direction, and links of equal length connected to each other and to said cranks at equal distances from their axes of rotation.

4. A mechanical movement comprising a pair of spaced revoluble cranks of equal length positioned at angles of fifty degrees to a straight line passing through their axes of rotation and on the same side thereof and oppositely directed relative to a perpendicular bisector of said line, and means for driving the same at equal angular velocities in the same direction, and links of equal length connected to each other and to said cranks at equal distances from their axes of rotation.

5. A mechanical movement comprising a pair of revoluble cranks of equal length hav-

ing their axes of rotation spaced apart a distance equal to five times their length, and means for driving the same at equal angular velocities in the same direction, said cranks being positioned at angles of fifty degrees to a straight line passing through their axes of rotation and on the same side thereof and oppositely directed relative to a perpendicular bisector of said line, and links of equal length connected to each other and to said cranks at equal distances from their axes of rotation.

6. A mechanical movement comprising a pair of spaced revoluble cranks of equal length positioned at angles of fifty degrees to a straight line passing through their axes of rotation and on the same side thereof and oppositely directed relative to a perpendicular bisector of said line, and means for driving the same at equal angular velocities in the same direction, and links of equal length connected to said cranks at equal distances from their axes of rotation, and to each other at a point lying in said perpendicular bisector and in a line perpendicular to either crank at its axis of rotation.

7. A mechanical movement comprising a pair of spaced revoluble cranks of equal length on spaced parallel axes and means for driving the same at equal angular velocities in the same direction, and links of equal length pivotally connected to said cranks at equal distances from their axes of rotation and connected to each other at the intersection of perpendiculars to said cranks at their axes of rotation when said cranks are positioned at an angle of fifty degrees to a straight line passing through their axes.

REUBEN ERICH.
